(57) **CLAIM**

The ornamental design for an earphone protective sleeve as shown and described.

DESCRIPTION

FIG. 1 is a top, front and left side perspective view of an earphone protective sleeve, showing my new design; FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is a top, front and left side perspective view of the earphone protective sleeve in a configuration of use.

The broken lines in the drawings depict portions of the earphone protective sleeve that form no part of the claimed design.

1 Claim, 10 Drawing Sheets
